Gustav Wedekind,
By atty. A. B. Strongton.

United States Patent Office.

GUSTAV WEDEKIND, OF PHILADELPHIA, PENNSYLVANIA.

Letters Patent No. 79,526, dated June 30, 1868.

IMPROVEMENT IN LAMP-SHADES.

The Schedule referred to in these Letters Patent and making part of the same.

TO ALL WHOM IT MAY CONCERN:

Be it known that I, GUSTAV WEDEKIND, of the city of Philadelphia, and State of Pennsylvania, have invented certain new and useful Improvements in Clasps for Lamp-Shades; and I do hereby declare the following to be a full, clear, and exact description of the construction and operation of the same, reference being had to the accompanying drawings, making a part of this specification, in which—

Figure 1 represents one of my lamp-shades and clasps, with a chimney shown in red lines, on which it is held, and by which the chimney is clasped at several points.

Figure 2 represents, in perspective, the clasp separated from the shade.

Figure 3 represents the shape and form of clasp as it is punched out of the metal, and before its radial arms are bent into position.

Similar letters of reference, where they occur in the separate figures, denote like parts in all of the drawings.

My invention consists in a lamp-shade clasp, having three sets of spring-arms, and punched, in a disk-form, in one piece, out of sheet metal, said arms being afterward bent into proper position for holding and steadyng the shade to itself, and itself to the chimney, without riveting or soldering, and thus very much facilitating the construction of the same, as well as the production of a clasp that is applicable to the varied sizes of chimneys in use, whether large or small.

To enable those skilled in the art to make and use my invention, I will proceed to describe the same with reference to the drawings.

The disk A is punched out of sheet brass, or other metal, with four radial arms, *a a a a*, four radial arms, *b b b b*, and eight short radial arms, *c*. I mention these numbers because I prefer to so make them, but a less number may be used. These radial arms, instead of being united at a common centre, are only united to the rim, and project towards a common centre. The rim may be recessed, embossed, and ornamented, in the act of punching the disk, or afterwards, so as to give it a conical form; as seen in fig. 1, which adds to its stiffness also.

When the disk is punched, embossed, &c., the arms *a* are bent upward, the arms *b* are bent downward, and the clasp being then arranged upon the top of the paper or other shade B, the arms *c* are bent down against the shade, so as to hold it to the clasp. The chimney C is inserted from below, and its tapered form springs out the arms *a* and *b*, which press against it with sufficient force to hold the shade to said chimney, but freely yield to any expansion of the glass as it becomes heated. The clasp is held to the chimney by eight spring-arms, which thus brace each other in pairs diametrically opposite to each other, and tend to hold thus more truly and firmly upon the chimney. The shade is also held to the clasp by eight clips, which keep it in true position. But, as before stated, whilst I prefer to use the eight spring-arms because they hold better, and prevent skewing of the shade, and because they adapt the clasp to chimneys of the largest as well as the smallest sizes, yet a less number may be used, as six, for instance, which is the common number, whilst eight, so far as I can learn, have never been used.

Having thus fully described my invention, what I claim therein as new, and desire to secure by Letters Patent, is—

A lamp-shade clasp, stamped out in a disk-form, in one piece, and with radial arms, which are bent into position to hold the shade to itself, and itself to the glass chimney, substantially as herein described and represented.

G. WEDEKIND.
